UNITED STATES PATENT OFFICE

EARLE S. MACPHERSON, OF DETROIT, MICHIGAN, ASSIGNOR TO HUPP MOTOR CAR CORPORATION, OF DETROIT, MICHIGAN, A CORPORATION OF VIRGINIA

MANIFOLD

Application filed October 13, 1924. Serial No. 743,443.

The invention relates to manifolds and has among its objects to provide a manifold for internal combustion engines which is of simple construction and effective in operation. A further object embodies a manifold and method of treating intake gases in which the intake gases are heated before introduction into the engine cylinders. A further object is to effectively utilize the exhaust 10 gases to heat the intake gases. A further object is to provide a combined intake and exhaust manifold suitable for use with an internal combustion engine having a plurality of aligned cylinders.

15 With these and other objects in view, the invention resides in the novel features of construction and combinations and arrangements of parts as more fully hereinafter described and claimed.

20 In the drawings which are made a part hereof and in which similar reference characters indicate corresponding parts:

Figure 1 is a front elevation showing the manifold attached to an engine;

25 Figure 2 is a plan view of the manifold;

Figure 3 is a side elevation of the manifold;

Figure 4 is a section view along the line 4—4 of Figure 1;

30 Figure 5 is a section view of the exhaust manifold along the lines 5—5 of Figure 1;

Figure 6 is a section view of the exhaust manifold along the lines 6—6 of Figure 1; and

35 Figure 7 is a section view of the exhaust manifold along the line 7—7 of Figure 1.

Referring to the drawings reference character 10 indicates the cylinder block of an internal combustion engine preferably of the

40 type having a plurality of aligned cylinders. Intake manifold 11 is preferably a metal casting and is provided with an intake passage 12 through which the gaseous mixture is conducted from the carburetor 13 of any

45 suitable type. The passage 12 extends upwardly and terminates in a T-shaped connection whereby the gases are divided at the point A and directed in opposite directions as indicated by the arms 14 and 15. The 50 arms are curved inwardly adjacent their

ends and terminate in the coupling sections 16 for connection by bolts 16' with the coupling sections 17 of the exhaust manifold 18. The exhaust manifold is preferably a metal casting and is provided with openings 19 55 adapted to abut the face of the cylinder block 10 for receiving the exhaust gases from the exhaust passages 20 of the cylinder block. While I have shown an internal combustion engine having eight cylinders it is obvious 60 that the number of cylinders might be varied without departing from the spirit of my invention.

The exhaust manifold is formed with arms 21 which conduct the intake gases in opposite 65 directions from the arm 14 to the outlets 22 for distribution to the intake ports (not shown) of the engine. The arm 15 likewise communicates with arms 23 terminating in outlets 24. The arms 21 and 23 are preferably cast below and integrally with the longitudinally extending exhaust passages 25 which receive the exhaust gases from passages 20 and openings 19 and conduct the 70 exhaust gases therefrom toward the center 75 of the casting. As shown particularly in Figures 5, 6 and 7, the exhaust gases passing through passages 25 are adapted to heat the intake gases in the arms 21 and 23, particularly at the points adjacent the exhaust passages 20, by reason of the dividing walls 26 separating the exhaust and intake passages forming hot spots.

As indicated at Figure 7 a hot spot B is provided at the point of division of the intake gases passing from arms 14 and 15 to the arms 21 and 23 respectively.

As shown particularly in Figure 4 the central portion of the exhaust manifold casting 18 is provided with a flanged portion 27 which 90 is secured to a flanged portion 28 of the intake manifold 11 by the bolts 29. The exhaust manifold is provided with a central baffle 30 against the opposite sides of which the exhaust gases strike after traveling toward the 95 center of the casting through passages 25 from the exhaust passages 20. The baffle 30 directs the exhaust gases in the same direction toward the point A to form a hot spot at the point of division of the intake gases 100

from the carburetor. The hot spot is formed by the exhaust gases striking the walls of the T-shaped connection at the point where the direction of flow of the intake gases, from the passage 12, is changed. After impinging upon the T-connection the exhaust gases from the passages 25 unite and flow through the common exhaust pipe 31 which is preferably bolted at 32 to the exhaust manifold casting.

10 In operation the exhaust gases enter the exhaust manifold 18 through passages 20 and 19 and flow from either end along passages 25 toward the baffle 30 at the center of the exhaust manifold casting. The baffle 30 directs the exhaust gases forwardly toward the T-connection of the intake manifold to form the hot spot A. The exhaust gases then pass out through the common exhaust pipe 31.

15 20 The intake gases from the carburetor 13 pass through passage 12 to the T-shaped connection at the point A where the gases are heated, as above described, and divide to pass through arms 14 and 15 to the second hot spots B. At the points B the intake gases again divide to flow through arms 21 and 23 and thence to outlets 22 connecting with the inlet ports of the engine (not shown). During their passage along arms 21, 23 the temperature of the intake gases is prevented from dropping by reason of the heated walls 26 separating the exhaust passages 25 from the arms 21, 23 of the intake manifold.

35 40 It will be noted that the exhaust gases uniformly heat the intake gases, the exhaust gases from half the cylinders of the engine heating the intake gases in the arms 21, while the gases of the other half heat the intake gases in the arms 23. The exhaust gases then unite to cause hot spot A, and thereafter are exhausted together.

45 50 While it is believed that from the foregoing description, the nature and advantages of my invention will be readily understood, I desire to have it understood that I do not limit myself to what is herein shown and described and that such changes may be resorted to when desired as fall within the scope of what is claimed.

55 60 What I claim as my invention is:

1. A manifold for internal combustion engines comprising an inlet passage for receiving a flow of intake gases, means for dividing the flow of gases into a plurality of branches, means for dividing each of said branches into a plurality of other branches, an outlet for said branches for communication with the engine intake, means for heating said gases at each of said points of division by means of the exhaust gases conducted in each case from those cylinders which are supplied by the intake gases passing the said respective points of division, and means for heating the gases during their flow between the last said point of division and

their said points of outlet to the engine intake while permitting them to pass from the first point of division to the second point of division without being heated.

2. In combination with an internal combustion engine having a plurality of exhaust ports, a manifold comprising an inlet passage for receiving a flow of intake gases, means for dividing the flow into a plurality of branches, means for dividing each of said branches into a plurality of other branches for distribution to the engine intake, means for conveying the exhaust gases from some of said exhaust ports adjacent some of the last said branches to heat the intake gases carried thereby, means for conveying the exhaust gases from the remainder of said exhaust ports adjacent other of the second mentioned branches to heat the intake gases carried thereby, means for uniting the exhaust gases, a baffle for directing the united exhaust gases adjacent the inlet passage of the intake gases for heating them directly at their first said point of division, and means for conducting away the united exhaust gases.

3. A manifold for internal combustion engines comprising an inlet passage for receiving a flow of intake gases, means for dividing the flow of gases into a plurality of branches, means for dividing each of said branches into a plurality of other branches, an outlet for each branch for communication with a plurality of cylinders, and means for conducting the exhaust gases from all of the cylinders of the engine into proximity with the said first point of division of the intake gases for heating said intake gases at the said first point of division, said exhaust gas conducting means also being arranged to heat the intake gases at each of said second points of division and at each outlet point.

4. The combination with an internal combustion engine, of a manifold including an exhaust passage arranged longitudinally of the engine for conducting exhaust gases from each end of the engine toward the center thereof, a baffle in the said exhaust passage for directing the exhaust gases through a single outlet, an intake passage adjacent the single exhaust outlet for receiving a flow of intake passages, the said intake passages being divided adjacent the single exhaust outlet to form a plurality of branches, the said intake passage being heated by the exhaust gases in the exhaust outlet at its point of division while the branches of the said intake passage are spaced from the exhaust passage, and auxiliary branches formed from each branch of the main intake passage, the said auxiliary branches being arranged adjacent the exhaust passage and being adapted to be heated thereby.

5. The method of treating the intake gases of an internal combustion engine which con-

sists in dividing the intake gases, applying heat at the point of division, allowing the gases to cool slightly after passing said point of division, dividing each of the divided portions aforesaid and applying heat at the last mentioned points of division, and to the last mentioned divided portions.

6. A manifold for internal combustion engines comprising an inlet passage for receiving a flow of intake gases, means for dividing the flow of gases into a plurality of branches, means for dividing each of said branches into a plurality of other branches, outlets for said branches for communication with the engine cylinders, means for conducting the exhaust gases from all of the cylinders of the engine into proximity with the said first point of division of the intake gases and for deflecting the exhaust gases directly against the said first point of division for heating the intake gases at the said point.

7. The combination with an internal combustion engine, of a main conduit for supplying intake gases to the entire engine, branch conduits extending from the said main conduit and auxiliary conduits extending from the said branch conduits and connecting into predetermined groups of cylinders, and means for utilizing the exhaust gases from the engine for forming a hot spot at a point intermediate the main conduit and the first mentioned branch conduits, other hot spots at points intermediate the branch conduits and the auxiliary conduits, and still other hot spots at points adjacent the outlet ends of the auxiliary conduits.

In testimony whereof I affix my signature.
EARLE S. MACPHERSON.
